(57) CLAIM

The ornamental design for a display panel with icon, as shown and described.

DESCRIPTION

FIG. 1 is a front view of a display panel with icon, showing my new design; and,

FIG. 2 is an enlarged front view thereof, the icon is shown separately for clarity of illustration.

The broken lines showing the display panel form no part of the claimed design.

1 Claim, 2 Drawing Sheets(56)
